[57] **CLAIM**

The ornamental design for a foundation wall outer moisture bar sheet or basement inner wall or floor humidity controlling lining sheet or the like, substantially as shown and described.

DESCRIPTION

FIG. 1 is a rear perspective view of a foundation wall outer moisture bar sheet or basement inner wall or floor humidity controlling lining sheet, or the like showing my new design, with the breaks indicating indeterminate dimensions;

FIG. 2 is a front perspective view;

FIG. 3 is an enlarged fragmentary rear perspective view;

FIG. 4 is a bottom plan view, taken from the left finished edge in FIG. 3; and

FIG. 5 is a left side elevational view, taken from the right finished edge in FIG. 3.

Fig. 1.

Fig. 2.

Fig. 5.
